(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The dashed-dotted broken lines show portions of an electronic device and form no part of the claimed design. The outermost dashed broken line(s) define the bounds of the claimed design and form no part thereof. All other broken lines showing text, icons, or other portions of the graphical user interface form no part of the claimed design.
